WAFFLE IRON

Walter E. Moore, St. Louis, Mo., assignor to Knapp-Mon-
arch Company, St. Louis, Mo., a corporation of Dela-
ware

Application September 20, 1954, Serial No. 32,359

Term of patent 14 years

(Cl. D81—10)

Fig. 1

Fig. 2

Fig. 3

Fig. 4

Figure 1 is a perspective view showing the front, top, and one side of a waffle iron embodying my new design;

Figure 2 is a perspective view showing the front, bottom and other side thereof;

Figure 3 is a side elevational view of the waffle iron in a vertical position resting on its rear end; and

Figure 4 is a rear end elevational view of the waffle iron.

The characteristic features of my design for the waffle iron disclosed reside in the front handle and the rear hinge, having the configuration and arrangement shown.

I claim:

The ornamental design for a waffle iron, substantially as shown.
